UNITED STATES PATENT OFFICE.

HARRY WACHENHEIMER, OF PROVIDENCE, RHODE ISLAND.

BRACELET.

Application filed July 1, 1925. Serial No. 40,903.

This invention relates to an improvement in the construction of chains or bracelets formed of a plurality of extendible links; and the object of this invention is the construction of such a chain or bracelet, the links of which telescope or slide one within the other rendering the same extendible in the direction of its length.

A further object of this invention is the provision of an inner connecting member 10 slidable in the outer member, the inner member being provided with a hook-shaped portion by which it may be readily connected to and disconnected from the next adjacent link of the bracelet.

A still further object of the invention is the provision of means whereby the hook member is prevented from being opened and the links disconnected when in contracted 20 position.

With these and other objects in view, the invention consists of certain novel features of construction, as will be more fully described, and particularly pointed out in the 25 appended claims.

In the accompanying drawings:

Figure 1 is a side elevation showing a portion of my improved bracelet, the ends of which are illustrated as provided with 30 means by which they may be connected to a wrist watch or the like.

Figure 2 is a perspective view illustrating the blank of the connector member of the bracelet as struck from sheet stock.

Figure 3 shows this connector blank as 35 having been folded into band or loop shape, one end being constructed in hook form and one side of the loop being adapted to be depressed to open the mouth of the hook.

Figure 4 is a perspective view illustrating the guide member of the bracelet link as struck from sheet stock.

Figure 5 shows this blank guide member as folded into channel shape.

Figure 6 is a central sectional top view 45 looking in the direction of the arrow showing the spring in contracted position and the members as extended.

Figure 7 is the same as Figure 6 and 50 showing the members of the bracelet as in closed position with the spring extended.

Figure 8 is a central sectional side elevation showing the parts in position as illustrated in Figure 6.

Figure 9 is a central sectional elevation 55 showing the parts in position as illustrated in Figure 7.

Figure 10 is a perspective view showing one of the links as bent up into position to be unhooked from the next adjacent link. 60

Figure 11 is a top or face view of the bracelet showing two of the links in contracted position.

Figure 12 is a top or face view of the bracelet illustrating the appearance of the 65 bracelet when its links are in extended position.

It is found in the construction and operation of bracelets of this construction which are adapted to be extended and also to have 70 their links detachably connected one to the other, of advantage to provide a guide member formed of sheet stock and folded to provide a broad, front face adapted to receive ornamentation and to slidably mount

a broad-faced, spring-pressed connector member in the guide member and to also form the connector member so that it will 75 perform the function of a hook for detachably connecting the different links together;

and it is also found of advantage to so arrange the parts of the links that the connector member cannot be opened and the links 80 detached one from the other except when the links are in extreme extended position;

and the following is a detailed description of the present embodiment of my present 85 invention and showing one means by which these advantageous results may be accomplished:

With reference to the drawings, 10 designates the guide link which is preferably formed of sheet stock blanked out first in the form illustrated in Figure 4, and subsequently folded into the position illustrated 90 in Figure 5, having a broad-faced front plate 11 with rearwardly-extending side walls 12, the edges of the side walls being turned inwardly to form flanges 13, one end of each of these side walls being formed

95 with an extending ear portion 14 and the other end with a corresponding depression 15 into which the adjacent end of the next link fits permitting of pivotal action between them.

One end of the broad plate of this link is also provided with an inwardly-extending abutment lug 16 against which one end

of the spring 17 may rest and this member is also provided with a cross bar 18 which extends between the pivot ears 14.

The connector member 19 is preferably 5 formed of sheet stock first blanked out into the shape illustrated in Figure 2, with a lip 20 at one end to form the hook and an opening 21 through its face. This blank 10 is folded substantially into band or loop 10 shape, as illustrated in Figure 3, having a broad bottom plate 22 and a top plate 23 slotted at 21, one end 24 of this band being folded preferably into hook shape having a tongue or lip member 25 adapted to be 15 hooked over the pin 18 of the next adjacent member 19 when the bottom plate 22 is depressed to permit such hooking and unhooking actions.

In assembling the parts, I form the guide 20 member into the shape illustrated in Figure 5, and the connecting member in the shape illustrated in Figure 3. I then place the coiled spring 17 sidewise into the connecting member, and then place this connecting member into the guide member and bend up the abutment lug 16 into the slot 21 of the connecting member to serve as an abutment for the end 27 of the spring while the end 28 thereof presses against the end 29 of the connecting member. I next assemble these links by simply snapping the hook of the connecting member of one link 30 over the connecting bar 18 of the guide member of the next adjacent link by which 35 simple action the links are detachably connected together.

It will be noted that when the link members are in contracted position such as is 40 illustrated in Figures 7 and 9, that the spring 17 prevents the inward bending of the bottom plate 22 of the connecting member thus effectually preventing the disengagement of the link members when they 45 are in contracted position, such disconnecting action necessitating that these members be first extended into the position illustrated in Figures 6 and 8, in which position this plate 22 may be bent inwardly, as illustrated in Figure 10, and also in dotted lines in 50 Figure 8.

By the inserting of the connecting pin 18 through the ears 14 of the side walls of the link and hooking the connecting member of the next adjacent link thereinto, a very 55 flexible pivot joint is provided.

My improved bracelet is very simple and practical and yet inexpensive to construct, it is also strong and durable and by providing a broad extending front face it 60 readily lends itself to receive a high degree of ornamentation which may render it very handsome and attractive in appearance.

The foregoing description is directed 65 solely towards the construction illustrated, but I desire it to be understood that I re-

serve the privilege of resorting to all the mechanical changes to which the device is susceptible, the invention being defined and limited only by the terms of the appended claims.

I claim:

1. A bracelet structure comprising a series of extendible links, each having a guide member formed of sheet stock and folded to provide a broad top wall and side walls, 70 and a connector member slidably mounted in said guide member and having a correspondingly broad top wall with a hook at one end by which it engages a portion carried by the guide member of the next adjacent link, said hook being manually detachable therefrom.

2. A bracelet structure comprising a series of extendible links, each having a guide member folded from sheet stock to provide a broad front face with rearwardly extending side wall having inturned flanges, a broad band connector member with a corresponding top wall formed in hook shape with a closing tongue and slidably mounted in said guide member between said face and flanges and adapted to be readily hooked into engagement with portions carried by the guide member of the next link, a spring acting between said members to press them into contracted relation, said spring serving to prevent the movement of the hook closing tongue when the links are in contracted relation.

3. A bracelet structure comprising a series of extendible links, each having a guide member with a broad front plate and rearwardly extending side walls, a connecting pin extending between said side walls, and a correspondingly broad faced spring pressed 100 connector member slidably mounted between the side walls of said guide member and having its broad face parallel to said front plate, a hook at one end of said connector engaging the connector pin of the guide member of the next link, a manually movable tongue for closing said hook whereby said members are detachably connected together.

4. A bracelet structure comprising a series of extendible links, each having a guide member formed of sheet stock folded to form a broad front face with rearwardly extending side walls, a connector pin extending laterally between said side walls, a connector member formed of sheet stock 115 folded into band shape to slide between said side walls of the guide member and having one wall slotted and having a hook at one end releasably engaging the pin of the next adjacent guide member, an abutment on said guide member extending through said slot, and a spring acting between said connector member and abutment to normally retain said link members in contracted position.

5. A bracelet structure comprising a series of extendible links, each having a guide member formed of sheet stock with a broad front face and rearwardly-extending side walls, a connector pin extending laterally between said walls, a connector member formed of sheet stock folded into band shape to slide between said side walls of the guide member and having one wall slot-
10 ted and having a hook at one end releasably engaging the pin of the next adjacent guide member, an abutment on said guide member extending through said slot, and a spring acting between said connector member and abutment to normally retain said link members in contracted position, said spring also serving to prevent the disconnecting of the link members except when in extended position.

15 In testimony whereof I affix my signature.

HARRY WACHENHEIMER.
